PROJECTILE FUSE

Pierre Henry, Geneva, Switzerland, assignor to
 Mefina S. A., Binningen, Switzerland, a corporation of Switzerland

Application May 10, 1938, Serial No. 207,085
 In Switzerland May 25, 1937

16 Claims. (Cl. 102—36)

This invention relates in general to improved safety mechanism for clockwork time fuses for projectiles and more particularly has reference to a clockwork time fuse for projectiles to be set for a fraction of a revolution. The hammer or firing pin of the fuse is tensioned by a spring and is held fast in this tensioned position by a centrifugally actuated bolt controlled by a time regulating member driven by the clockwork until 10 at the end of a period corresponding to a previously adjusted setting, the time regulating member releases the bolt held against the centrifugal force acting thereon, so that the now freely movable hammer or firing pin is projected 15 under the action of the spring against the detonator and effects the explosion of the projectile.

In such fuses it is known to lock the hammer or firing pin holding bolt, in addition to the time regulating member, by the provision of a second bolt which, on firing the projectile, will, due to its inertia, move to an inoperative position and thereby release the hammer holding bolt. This additional safety mechanism is intended to 25 render the projectile safe during transportation, in that any premature explosion thereof is prevented, even if the clockwork should inadvertently come into operation.

There are, however, serious defects in the known fuses, due to the safety means coming into operation through their inertia, especially the deficient security after setting, since the resistance, which has to be overcome by inertia bolts at their change of position, cannot be selected at will, but must be a function of the acceleration of the projectile arising at the firing thereof. Thus, in fuses for projectiles having low initial speed, an unintentional release may occur, for example, through accidental dropping 40 of an already set projectile from even a low height of a few decimeters. Such projectiles might, as the release is not outwardly visible, immediately explode at a subsequent alteration of the setting.

An object of the present invention is to devise a safety mechanism free from this defect and which provides for complete security, both during the setting operation and during the transportation of a projectile in the set condition.

Another object of this invention is to provide a fuse, the setting of which can be altered or put back at any time without danger independently of the previous set period, as only a running down of the time regulating member and a simul-

taneous minimum rotation of the projectile can effect the release of the hammer or firing pin.

A further object is to provide a construction in which the safety bolt on one side fixes the zero position of the setting and on the other side is itself locked in this zero position by the time regulating member against accidental release.

Still another object is to provide a safety mechanism so constructed that through its positive release it immediately allows the setting, but 10 on the return of the time regulating member to the zero position it again automatically assumes the locked position when it is not subjected to centrifugal force exceeding a given amount, which secures it in the released position and so 15 renders the release of the hammer or firing pin possible.

With these and other important objects in view, which may be incident to my improvements, the invention resides in the parts and 20 combinations to be hereinafter set forth and claimed, with the understanding that the several necessary elements comprising my invention may be varied in construction, proportions and arrangement, without departing from the spirit 25 and scope of the appended claims.

An example of construction of the invention is illustrated in the accompanying drawing, in which:

Figure 1 is an axial sectional view taken 30 through the lower part of a time fuse according to the present invention.

Fig. 2 is a sectional and partial top view taken on the line II—II of Fig. 1 and shows the safety members in the zero position.

Fig. 3 is a view similar to Fig. 2 showing the positions of the members at the maximum setting.

Fig. 4 is another view similar to Fig. 2 showing the position of the members during the flight of 40 the projectile immediately before the disengagement of the hammer locking bolt.

As shown in the drawing, the fuse comprises a framework 1 mounted in a casing 2. The lower end of the framework is provided with a sleeve 45 12, in which the hammer or firing pin 10 is slidably mounted.

Hammer or firing pin 10 is subjected to the action of the tensioned spring 11 and is prevented by the bolt 13 from axial forward movement in the guiding sleeve 12 against the detonator (not shown). Bolt 13 is mounted for swinging movement on an axle 14 and tends to swing outwardly thereon under the action of centrifugal force produced by rotation of the 55

projectile. The inner edge of the bolt 13 engages in a notch 15 of the hammer or firing pin 10, while the tip 16 of its outer edge bears against the inner face of an annular abutment 17 of a 5 toothed crown 18. The toothed crown together with its abutment 17 form the time regulating member which, by means of a pinion 19, is in connection both with the driving shaft 20 of the clockwork and with exterior setting members (not 10 illustrated).

In the annular abutment 17 of the toothed crown 18 is a gap 21 (Fig. 3), which extends about one-twelfth of its circumference and is so formed that at one end the end surface 22 forms an 15 acute angle with the inner wall of the abutment 17, and at the opposite end the end surface 25 forms an acute angle with the outer wall of the abutment, as can be seen from Fig. 3.

In the toothed crown 18 a space between two 20 teeth is omitted (no space formed between two adjacent teeth) at a place previously determined by the position of the gap 21, so that an abutment 24 is there formed which cooperates with pinion 19 to limit rotation of crown 18. This 25 fixes the maximum setting, which is effected by a counter-clockwise rotation of crown 18 from the position of Fig. 2, so that the gap 21 cannot in any case during the setting operation come before the tip 16 of the swinging bolt 13 to permit said bolt to swing out of notch 15 and thereby release the hammer 10 (see Fig. 3).

Under the swinging bolt 13 in the breech 25 of the fuse, a radial recess 26 is provided in which a second bolt 27 is slidably mounted and urged inwardly by a spring 28. This bolt 27, which is the safety bolt, is provided with a head 29 having an inner surface 30 inclined with respect to the radial central plane of the bolt. The outer surface 31 of the safety bolt head opposite the surface 23 of the abutment 17 is shaped so that in the zero position (Fig. 2) these two surfaces harmonize, being placed obliquely against the direction of force, the parts having the position illustrated in Fig. 2. In this zero position 40 the safety bolt 27, which is at its innermost radial position, prevents a clockwise rotation of the toothed crown 18, while, due to the wedging action of the surface 23 of the toothed crown abutment on the surface 31 of the safety bolt, an effectual locking of the whole safety system is obtained. It will be noted that in this locked or zero position, the inner surface of abutment 17 adjacent the end 32 prevents outward movement 45 of the locking bolt 13. This locking of the system can only be released by setting of the fuse, when the time regulating member is rotated counter-clockwise against the motive power of the clockwork. Upon counter-clockwise rotation of the toothed crown, the tip 32 of the toothed crown abutment slides along the surface 30 of the safety bolt and thereby shifts the safety bolt 27 against the action of the spring 28 into the position shown in Fig. 3. In the case of an 50 eventual setting back to zero—that is, upon a clockwise rotation of the toothed crown—the safety bolt, due to the action of the spring 28 (no centrifugal force acting on the bolt), automatically moves back into the original locking position. It will be seen that the bolt 13 can 55 therefore arrive in the notch 21 and release the hammer or firing pin 10 only when the safety bolt 27, as shown in Fig. 4, is urged radially outwardly by centrifugal force against the action of the spring 28 and when the toothed crown 60 through the action of the clockwork has rotated

some degrees clockwise beyond the zero position (Fig. 2). In the zero position, as can be seen from Fig. 2, a distance between the pinion 19 and the shoulder 24 of the toothed crown must remain corresponding to a rotation through a 5 few degrees of the toothed crown.

The function of the safety bolt 27 is fourfold:

Firstly, as can be seen from Fig. 2, the safety bolt when not subjected to centrifugal force fixes the zero position of the setting, as it prevents the 10 toothed crown 18 from a further clockwise rotation, which might result in the release of the hammer bolt 13 under the effect of an accidental lateral blow on the projectile. This, of course, would cause the immediate explosion of the projectile. 15

Secondly, the safety bolt 27 is locked in the zero position of the setting (Fig. 2) against any accidental release.

Thirdly, the safety bolt 27 will allow counter-clockwise rotation of the toothed crown, as is necessary at setting, and will again return automatically under the action of spring 28 into the locking position shown in Fig. 2 upon the reversal of the rotation of the toothed crown. 20

Fourthly, the safety bolt 27 must, upon the rotation of the projectile during flight, move to a position under the action of centrifugal force thereon, as soon as this force is greater than the opposing force of the spring 28, at which position said safety bolt 27 will not check the desired release of the hammer or firing pin locking bolt 13. 25

It is obvious that instead of the radially movable safety bolt 27, any other member removable from the path of the time regulating member can also be employed, for example, an eccentrically mounted swinging bolt. 30

While I have shown and described the preferred embodiment of my invention, I wish it to be understood that I do not confine myself to the precise details herein set forth by way of illustration, as it is apparent that many changes and variations may be made therein by those skilled in the art, without departing from the spirit of 40 the invention or exceeding the scope of the appended claims. 45

I claim:

1. A safety mechanism for clockwork time fuses of projectiles, comprising a rotary clockwork driven time setting control member, a safety bolt adapted to be displaced by centrifugal force when the projectile is in flight, means urging said bolt to an inner position when not subjected to the centrifugal force of flight, and means on said safety bolt cooperating with the setting control member when the bolt is in its inner position for limiting rotary movement of said member in a given direction to determine the zero position of said member and for locking 50 said bolt against accidental release, said means on the bolt permitting movement of the setting member in an opposite direction but acting in the absence of centrifugal force on said bolt to again limit movement in said given direction 55 beyond the zero setting, said bolt when subjected to centrifugal force being displaced to shift the means carried thereby out of cooperative engagement with said member.

2. A safety mechanism for clockwork time fuses of projectiles, comprising a rotary clockwork driven time setting control member, a safety bolt normally in a position to block rotation of the control member in its driven direction beyond a given limit, said safety bolt being adapted 70 to centrifugal force being displaced to shift the means carried thereby out of cooperative engagement with said member. 75

to be moved outwardly by centrifugal force when the projectile is in flight to permit driven rotation of said control member beyond the given limit, and cooperating means on said safety bolt 5 and control member operable upon rotation of the control member in a direction opposite from that in which it is driven for displacing the safety bolt outwardly to permit such opposite rotation for setting the control member.

10 3. A safety mechanism for clockwork time fuses of projectiles, comprising a rotary clockwork driven time setting control member, a safety bolt, means urging said safety bolt to a position to block rotation of the control member in its driven direction beyond a given limit, said safety bolt being adapted to be moved outwardly by centrifugal force when the projectile is in flight to permit driven rotation of said control member beyond the given limit, and cooperating means on said safety bolt and control member operable upon rotation of the control member in a direction opposite from that in which it is driven for displacing the safety bolt outwardly against said urging means to permit such opposite rotation for setting the control member.

4. A safety mechanism for clockwork time fuses of projectiles, comprising a rotary clockwork driven time setting control member, a radially movable safety bolt, means urging said safety bolt to a position to block rotation of the control member in its driven direction beyond a given limit, said safety bolt being adapted to be moved outwardly by centrifugal force when the projectile is in flight to permit driven rotation of said control member beyond the given limit, and cooperating means on said safety bolt and control member operable upon rotation of the control member in a direction opposite from that in which it is driven for displacing the safety bolt outwardly against said urging means to permit such opposite rotation for setting the control member.

5. A safety mechanism for clockwork time fuses of projectiles, comprising a rotary clockwork driven time setting control member, a safety bolt normally in a position to block rotation of the control member in its driven direction beyond a given limit, said safety bolt being adapted to be moved outwardly by centrifugal force when the projectile is in flight to permit driven rotation of said control member beyond the given limit, and means for locking said safety bolt against outward movement when in blocking engagement with said control member.

55 6. A safety mechanism for clockwork time fuses of projectiles, comprising a rotary clockwork driven time setting control member, a safety bolt normally in a position to block rotation of the control member in its driven direction beyond a given limit, said safety bolt being adapted to be moved outwardly by centrifugal force when the projectile is in flight to permit driven rotation of said control member beyond the given limit, cooperating means on said safety bolt and control member operable upon rotation of the control member in a direction opposite from that in which it is driven for displacing the safety bolt outwardly to permit such opposite rotation for setting the control member, and means for locking said safety bolt against outward movement when in blocking engagement with said control member.

70 7. A safety mechanism for clockwork time fuses of projectiles, comprising a rotary clockwork driven time setting control member, a safety bolt

normally in a position to block rotation of the control member in its driven direction beyond a given limit, said safety bolt being adapted to be moved outwardly by centrifugal force when the projectile is in flight to permit driven rotation of said control member beyond the given limit, and means including a surface on said safety bolt oblique to the direction of movement of said safety bolt and a surface on the control member oblique to the circumferential movement of said member adapted to cooperate with the oblique surface on the safety bolt to urge the bolt inwardly upon engagement of said oblique surfaces and the exertion of pressure on said bolt by the control member, whereby outward movement of said safety bolt is blocked.

8. A safety mechanism for clockwork time fuses of projectiles, comprising a rotary clockwork driven time setting control member, a safety bolt normally in a position to block rotation of the control member in its driven direction beyond a given limit, said safety bolt being adapted to be moved outwardly by centrifugal force when the projectile is in flight to permit driven rotation of said control member beyond the given limit, and cooperating means on said safety bolt and control member operable upon rotation of the control member in a direction opposite from that in which it is driven for displacing the safety bolt outwardly to permit such opposite rotation for setting the control member, said control member having a toothed portion, a pinion meshing with said toothed portion, and an abutment carried by said toothed portion for limiting rotation thereof.

9. A safety mechanism for clockwork time fuses of projectiles, comprising a rotary clockwork driven time setting control member, a safety bolt normally in a position to block rotation of the control member in its driven direction beyond a given limit, said safety bolt being adapted to be moved outwardly by centrifugal force when the projectile is in flight to permit driven rotation of said control member beyond the given limit, and cooperating means on said safety bolt and control member operable upon rotation of the control member in a direction opposite from that in which it is driven for displacing the safety bolt outwardly to permit such opposite rotation for setting the control member, said control member having a toothed portion, a pinion meshing with said toothed portion, and an abutment formed on said toothed portion by the omission of a space between two adjacent teeth and adapted to cooperate with said pinion for limiting the rotation of said member.

10. A safety mechanism for clockwork time fuses of projectiles, comprising a rotary clockwork driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, and a blocking cam surface formed on said rotary control member and inclined to engage and cooperate with the blocking cam surface of the safety bolt when said safety bolt is in its innermost position, to retain the safety bolt in its innermost position, and to block rotation of said member in the direction in which it is driven by the clockwork.

11. A safety mechanism for clockwork time fuses of projectiles, comprising a rotary clock-

- work driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, a blocking cam surface formed on said rotary control member and inclined to engage and cooperate with the blocking cam surface of the safety bolt when said safety bolt is in its innermost position, to retain the safety bolt in its innermost position, and to block rotation of said member in the direction in which it is driven by the clockwork, a releasing cam surface formed on said safety bolt extending obliquely to the direction of movement thereof, and a releasing cam surface formed on said rotary control member and inclined to cooperate with the releasing cam surface of said safety bolt upon rotation of the control member in a direction opposite from that in which it is driven by the clockwork to displace the bolt outwardly.
12. A safety mechanism for clockwork time fuses of projectiles, comprising a rotary clockwork driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, and a split annular flange carried by said rotary member, one end face of said annular flange being inclined to form a blocking cam surface adapted to engage and cooperate with the blocking cam surface of the safety bolt when said safety bolt is in its innermost position, to retain the safety bolt in its innermost position, and to block rotation of said member in the direction in which it is driven by the clockwork.
13. A safety mechanism for clockwork time fuses of projectiles, comprising a rotary clockwork driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, a split annular flange carried by said rotary member, one end face of said annular flange being inclined to form a blocking cam surface adapted to engage and cooperate with the blocking cam surface of the safety bolt when said safety bolt is in its innermost position, to retain the safety bolt in its innermost position, and to block rotation of said member in the direction in which it is driven by the clockwork, a releasing cam surface formed on said safety bolt extending obliquely to the direction thereof, a releasing cam surface formed on the other end of said annular flange and inclined to cooperate with the releasing cam surface of said safety bolt upon rotation of the control member in a direction opposite from that in which it is driven by the clockwork to displace the bolt outwardly.
14. In a device of the character described, a firing pin, a centrifugally actuated bolt for locking and releasing the firing pin, a rotary clockwork driven time setting control member, a safety bolt mounted for movement outwardly by cen-

trifugal force produced by rotation of the projectile in flight, means urging said safety bolt to an inner position when not subjected to centrifugal force, a blocking cam surface formed on said safety bolt and extending obliquely to the direction of movement of said safety bolt, a split annular flange carried by said rotary member, one end face of said annular flange being inclined to form a blocking cam surface adapted to engage and cooperate with the blocking cam surface of the safety bolt when said safety bolt is in its innermost position, to retain the safety bolt in its innermost position, and to block rotation of said member in the direction in which it is driven by the clockwork, and means on the locking bolt engaging said split flange for retaining said locking bolt in locked position until the split in the flange is reached.

15. In a device of the character described, a firing pin, a centrifugally actuated bolt for locking and releasing said firing pin, a rotary clockwork driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, a split annular flange carried by said rotary member, one end face of said annular flange being inclined to form a blocking cam surface adapted to engage and cooperate with the blocking cam surface of the safety bolt when said safety bolt is in its innermost position, to retain the safety bolt in its innermost position, and to block rotation of said member in the direction in which it is driven by the clockwork, a releasing cam surface formed on said safety bolt extending obliquely to the direction thereof, a releasing cam surface formed on the other end of said annular flange and inclined to cooperate with the releasing cam surface of said safety bolt upon rotation of the control member in a direction opposite from that in which it is driven by the clockwork to displace the bolt outwardly, and means on the locking bolt engaging said flange for retaining said locking bolt in pin-locking position until the split in the flange is reached.

16. In a device of the character described, a firing pin, a centrifugally actuated bolt for locking and releasing said firing pin, a rotary clockwork driven time setting control member, a safety bolt mounted for movement outwardly by centrifugal force produced by rotation of the projectile in flight, means urging said safety bolt to an inner position when not subjected to centrifugal force, a blocking cam surface formed on said safety bolt and extending obliquely to the direction of movement of said safety bolt, a split annular flange carried by said rotary member, one end face of said annular flange being inclined to form a blocking cam surface adapted to engage and cooperate with the blocking cam surface of the safety bolt when said safety bolt is in its innermost position, to retain the safety bolt in its innermost position, and to block rotation of said member in the direction in which it is driven by the clockwork, a releasing cam surface formed on said safety bolt extending obliquely to the direction thereof, a releasing cam surface formed on the other end of said annular flange and inclined to cooperate with the releasing cam surface of said safety bolt upon rotation of the control member in a direction opposite from that in which it is driven by the clockwork to displace the bolt outwardly.

which it is driven by the clockwork to displace the bolt outwardly, means on the locking bolt engaging said flange for retaining said locking bolt in pin-locking position until the split in the flange is reached, said safety bolt when not subjected to centrifugal force serving to block movement of said flange in one direction to bring the

split therein to a position to permit release of the locking bolt, and means for limiting movement of the flange in the opposite direction to prevent the split reaching a position to release the locking bolt.

PIERRE HENRY. 5
